UNITED STATES PATENT OFFICE.

EDWARD GERRARD, OF INDIANAPOLIS, INDIANA, ASSIGNOR TO THE NATIONAL DRY KILN COMPANY, OF INDIANAPOLIS, INDIANA, A CORPORATION OF INDIANA.

STEAM-TRAP.

SPECIFICATION forming part of Letters Patent No. 742,308, dated October 27, 1903.

Application filed April 21, 1903. Serial No. 163,673. (No model.)

To all whom it may concern:

Be it known that I, EDWARD GERRARD, a citizen of the United States, residing at Indianapolis, in the county of Marion and State 5 of Indiana, have invented certain new and useful Improvements in Steam-Traps, of which the following is a specification.

The object of my invention is to produce an efficient but easily-constructed valve especially designed for steam-traps, by means 10 of which the discharge-outlet may be automatically varied by the accumulating condensed water.

The accompanying drawings illustrate my 15 invention.

Figure 1 is a central vertical sectional view of the steam-trap with the valve shown in elevation, and Fig. 2 is an enlarged vertical section of the valves.

20 In the drawings, 10 indicates a suitable box or casing provided with the usual steam-inlet 11, drainage-outlet 12, water-outlet 13, and cap 14. Casing 10 is also provided with a pair of openings 15 15, at which points a suitable gage-glass may be attached. Outlet 13 does not communicate directly with the interior of the casing 10, but communicates therewith through a channel 16, formed in cap 14 and communicating with an opening 17, into 25 which is secured one end of a tube 18, which extends downward to a point near the bottom of casing 10. The upper end of tube 18 is closed by a plug 19, having a central vertical bore 20, with a valve-seat 21 formed at the lower end thereof. Adapted to seat in valve-seat 21 is the conical head 22 of a hollow cone-valve 23, provided with a bore 24, somewhat less in diameter than the bore 20. The cone-valve 23 is adapted to vibrate vertically 30 within tube 18 and is held in alinement with valve-seat 21 between wings 18', formed in the tube 18. Nested within the cone-valve 23 is a second cone-valve, 25, provided with a conical head 26, which seats within a valve-seat 24', formed at the lower end of bore 24. Cone-valve 25 is hollow and is provided with a vertical bore 26, which is smaller than bore 24, but alines therewith, and which has a valve-seat 26' formed at the lower end. Adapted

35 to seat within valve-seat 26' is a pin-valve 27, 50 provided with a conical head 27', which seats within the valve-seat 26'. Pin-valve 27 is carried at the upper end of a rod 28, which at its lower end is pivoted to the short arm of a lever 29, pivoted at 30 to tube 18 and carrying at the end of its long arm a float-ball 31. Pin-valve 27 carries a pair of cross-arms, which project through slots 32 in the cone-valve 25 and aline with slots 33 in cone-valve 23, the slots 32, however, being of less 60 length than the slots 33 and of greater length than the diameter of pin 27".

In operation the weight or ball 31 normally holds pin-valve 27 into seat 26', cone 26 into seat 24', and cone 22 into seat 21. As the 65 water accumulates in casing 10 and finally rises above the lower end of tube 18, so as to seal the same, ball 31 rises and draws pin-valve 27 downward, so as to open bore 26, and the water is forced by the steam-pressure 70 within casing 10 upward through tube 18 and is discharged through bore 26, bore 24, and bore 20 into passage 16 and from thence out through the discharge-outlet 13, the pressure and flow of the water being sufficient to keep 75 cone 26 into the seat 24' and cone 22 into seat 21. If the water continues to accumulate, ball 31 will be raised farther, so as to bring pin 27" into engagement with the lower end of slots 32, and thus draw valve 25 downward, 80 so as to open bore 24, and if this is not sufficient to allow the water to escape as rapidly as it accumulates ball 31 will continue to rise until pins 27" come into contact with the lower ends of slot 33, so as to pull valve 23 downward, 85 thus opening bore 20, whereupon the maximum discharge will take place. As the water decreases within the casing 10 the ball 31 will drop, and the valves 23 and 25 will be returned in the order named by the pressure 90 of water passing therethrough.

It will be noted that by reason of the nesting of the several valves a single operating rod and lever is all that is required.

It will be readily understood that the number of nested valves may be multiplied to any desired extent, according to the conditions under which the apparatus is to work.

I claim as my invention—

1. In a steam-trap, the combination, with the main receiving-casing, of a cylinder having an opening in its top and extending downward into said casing, a valve mounted in the casing and normally closing the opening in the upper end thereof, said valve consisting of a plurality of nested valve members, and means for automatically moving said valve members in succession, for the purpose set forth.

2. In a valve structure of the class described, the combination, with the main receiving-casing and a cylinder having an opening in its top and extending downward into said casing, of a plurality of hollow cone-valves nested

one within the other in the open upper end of said cylinder and having alined successively-decreasing bores, a rod carrying an innermost valve, a connection between said rod and the outer valve members, whereby said outer valve members may be operated by said rod in succession, and means for operating said rod.

In witness whereof I have hereunto set my hand and seal, at Indianapolis, Indiana, this 16th day of April, 1903.

EDWARD GERRARD. [L. S.]
